UNITED STATES PATENT OFFICE.

GEORGE WILLIAM YOUNG, OF BULWICH, LONDON, ENGLAND.

MACHINE FOR AUTOMATICALLY GATHERING AND COLLATING SHEETS AND THE LIKE.

Application filed January 13, 1928, Serial No. 246,605, and in Great Britain January 20, 1927.

This invention relates to automatic rotary gathering and collating machines for the use of printers and others, of the kind comprising a rotary framework or carrier adapted to 5 carry the piles of sheets to be gathered, and suction means adapted to lift the top sheet from each pile in succession and deposit it upon a conveyor by which the sheets are transferred to a packing device.

10 The object of this invention is to provide an improved and simplified construction of such machine which shall be equally adapted for handling single or folded sheets. A further object is to provide a machine of the 15 kind specified which shall be more compact and have a larger capacity than previously known machines.

As will readily be understood when suction devices applied from above are used for 20 lifting folded sheets or signatures there is a tendency for the under part of the sheet to sag and interfere with the proper working of the machine.

Accordingly the present invention consists 25 in providing in association with the sheet lifting devices means to support from the underside the sheets carried by the sheet lifting devices. Suitable mechanism is provided to ensure the withdrawal or removal 30 of the said support means when the sheets are deposited on the conveyor band and to replace them under the next sheet lifted. The movement executed by the sheet lifting devices in transferring sheets from the 35 rotary carrier to the conveyor band may take any desired form but preferably includes a vertical movement in taking the sheet from the carrier and a horizontal movement in transferring the sheet to a position over the 40 conveyor.

The invention is hereinafter more fully explained with reference to the accompanying drawings in which one practical form of construction of my improved sheet gathering and collating machine is illustrated.

In these drawings:—

Fig. 1 is a side elevation of an improved sheet gathering and collating machine constructed and arranged in accordance with 50 this invention.

Fig. 1^a is a detail elevation of the same from the reverse side and on a larger scale.

Fig. 2 is a plan of the same.

Fig. 2^a is a detail plan of the same corresponding with Fig. 1^a, on a larger scale. 55

Fig. 3 is a fragmentary side elevation showing the parts in different position,

Figs. 4 and 5 are plan views of one of the sheet lifting devices with the sheet supporting fingers in different positions and 60

Figs. 6, 7 and 8 are front elevations of one of the sheet lifting devices the views being taken at different phases in the cycle of operation of the machine.

Referring to these figures it will be seen 65 that the improved sheet gathering and collating machine comprises a wheel-like carrier *a* mounted to rotate about a horizontal axis and having pivotally suspended at points around its periphery cradles *a'* on 70 which the piles of sheets are supported. In the example illustrated each cradle is designed to carry four piles of sheets, and sheet lifting and transferring devices *c* corresponding in number to the piles of sheets 75 on the cradles are arranged to operate on opposite sides of the rotary carrier. Rotary motion is imparted to the carrier *a* through worm and worm wheel gearing *b* connecting it to a drive shaft *b'* which may be fitted 80 with fast and loose belt pulleys *b*².

The suction sheet-lifting devices are arranged to move first horizontally towards the axis of the rotary carrier, descend vertically on to the piles of sheets on the cradles, then lift vertically from said piles and move horizontally back to position over conveyor bands which assemble the sheets in the required sequence in packing devices provided for their reception. For this purpose 90 the machine frame extends in opposite directions from the axis of the rotary carrier *a* and the terminal portions of the frame are each provided with equally spaced channel-shaped guide-ways *d* along which move 95 slides *e* operatively connected by links *f* and levers *f'* to oscillating cross shafts *f*². The various slides on each side of the machine may be connected by a cross bar (not shown) and rotary pinions *e'* mounted on the slides 100 may be arranged to mesh with fixed horizontal racks *e*² to ensure unison of movement throughout the slides. Oscillatory motion

is imparted to the cross shafts *f*² by cams *g* through the medium of levers *g'* and links 105 *g*², the cam shafts being connected through

bevel or other suitable gearing g^3 with the drive shaft b' of the machine. The suction sheet lifting devices c are mounted upon travellers c' arranged to detachably engage and move with the slides e along the guide-ways d .

Between the rotary carrier a and the near ends of the guide-ways d vertically reciprocating columns h are provided having short 10 horizontal channel-shaped guides h' which when raised come into register with the guide-ways d and receive the travellers c' projected forwardly by the slides e after which the descending movement of the columns causes the connection between the travellers c' and the slides e to be severed until the columns rise again after the sheet lifting operation and re-establish said connection. This connection is effected by a vertical 20 cal pin c^2 in the one part engaging a corresponding hole in the other part in a manner permitting separation when the traveller descends, whilst maintaining a positive connection of the parts when aligned horizontally.

The columns h are hollow and guided by central guide rods h^2 and bear by gravity upon cross-heads h^3 oscillated vertically by cams i operating through lever mechanism 30 i' , the cams being driven through spur gearing (not shown) connecting with the shafts of the cams g . In order to achieve a rapid vertical movement in the columns without throwing undue stress on the cam i the gearing is so arranged that the cam i rotates twice as fast as the cam g . Hence the columns descend idly between every two successive operative descents.

The connection between the vertically oscillating columns h and the rocking levers i' is such as to permit of some lost motion between the parts in order that when the sheet lifting devices come into contact with the piles of sheets the motion of the levers 40 may continue unimpeded. In this way effective contact is established between the lifting devices and the sheets at each cycle of operations regardless of the variation in height of the different piles.

Extending transversely of the terminal portions of the machine frame is an endless band conveyor j which receives the sheets from the suction lifting devices and assemble them in packers (not shown). Said conveyor is driven by chain and sprocket gear j' from the main drive shaft b' .

Where small sheets only are to be handled the sheet lifting devices may comprise single suction plates but to enable sheets of varying sizes to be dealt with effectively each sheet lifting device preferably comprises as shown in Figs. 4 to 8 two or more suction plates k adjustably mounted upon a hollow bar k' engaged with the traveller c' , each plate having on its underside a rubber suc-

tion cup k^2 communicating through pipe connections k^3 with the interior of the bar k' which forms a suction conduit connected by a flexible tube to a pump (not shown). Each suction plate has a set screw k^4 whereby it may be secured in any desired adjusted position on the bar k' .

The sheet supporting means which form a characteristic feature of this invention comprise fingers l pivotally mounted on the 75 suction plates and arranged to swing in horizontal planes close under the sheet as the latter is lifted from its pile and to remain in a position for supporting the sheet until the latter is over the conveyor band j 80 whereupon they are withdrawn from under the sheet-lifting device until next lifting operation.

The required movements are imparted to these fingers by pistons m operating in air 85 cylinders m' mounted on the top of the suction plates, the pistons being connected by links m^2 to cranks l' rigid with the fingers l and operated by suction and pressure alternately conveyed through the hollow bar 90 k' and the flexible conduit. Communication between the suction pipe k^3 and the interior of the cylinders m' is controlled by taper plug valves n normally retained in an open position by the action of tension 95 springs n' but adapted to be turned to a closed position as shown in Fig. 7 when contact is established between the sheet lifting device and the pile of sheets. For this purpose a crank pin n^2 projecting from the plug 100 of the valve n is operatively engaged between pins o projecting laterally from a plunger o' sliding vertically in a guide aperture in the suction plate and depending from the underside thereof for contact with 105 the pile of sheets. A gravity catch lever p pivotally supported upon the hollow bar k' and a spring influenced plunger p' are arranged to assist in controlling the movements of the fingers l in a manner herein- 110 after described.

As the sheet lifting devices move from over the conveyor j towards the cradles their sheet supporting fingers are in the retracted position and retained against movement by 115 the gravity catch lever p and though suction exists throughout the conduit and such suction acts upon the pistons, the fingers l are unable to move because they are held back by the gravity catch lever p . Fig. 6 illustrates the parts during this period of the cycle of operation. When the sheet lifting device drops on to the pile of sheets the plunger o' is pressed upwardly causing the valve n to be closed temporarily and at the same time the gravity catch lever p , by contact with the sheets, is raised from in front of the fingers l as shown in Fig. 7. It will be noted that the pile of sheets is so placed 125 that the gravity catch lever engages the backs 130

or folded edges of the signatures and is therefore maintained in a raised position as the sheet is lifted by the suction cups k^2 whilst the plungers o' engage the corners of 5 the sheets along the cut edges and therefore descend under the action of the springs n as the suction devices lift from the piles thereby opening the valves n and causing the fingers to swing in under the sheet. The 10 parts now remain in this position until on coming over the conveyor band j the spring influenced plunger p' is depressed by engagement with a cam track q on the machine frame said plunger bearing upon the tail 15 of the catch lever and temporarily supporting the weight of the gravity catch lever p as shown in Fig. 8. The suction conduit is now temporarily connected by suitable valve mechanism to the compression side of the 20 pump so that a wave of air pressure acts in forcing back the fingers l to the retracted position. At the same time a ball valve r is blown down into a valve seating within the rubber suction cup k^2 thus cutting off the 25 air suction from the top of the sheet which is allowed to fall to the conveyor below. This air pressure is continued whilst the suction lifting device moves forward sufficiently for the plunger p' to clear the cam q and 30 allow the catch lever p to descend to a normal position whereupon the air pressure is cut off and suction resumed.

I claim:—

1. An automatic sheet gathering and collating machine, comprising a rotary carrier having suspended cradles, sheet lifting means provided with means to support from the underside work sheets carried by said sheet lifting means and means whereby said sheet lifting means are reciprocated vertically over the cradles.
2. An automatic sheet gathering and collating machine comprising a rotary carrier with suspended cradles, sheet lifting means guided rectilinearly towards and from said carrier, means whereby said sheet lifting means are reciprocated vertically over the cradles, and sheet supporting fingers co-operating with the sheet lifting devices.
3. An automatic sheet gathering and collating machine according to claim 2 where-

in the means for actuating the sheet lifting devices and the sheet supporting fingers are pneumatically operated.

4. An automatic sheet gathering and collating machine as claimed in claim 2, including a sheet gathering conveyor band, travelers whereby the sheet lifting devices are carried and horizontal guideways extending over the sheet gathering conveyor 60 band and on which said travelers operate.

5. An automatic sheet gathering and collating machine, comprising a rotary carrier having suspended cradles, sheet lifting means, vertically reciprocating columns by 65 which said sheet lifting means are lowered on to the cradles, a sheet gathering conveyor band, horizontal guideways extending over said band, travelers whereby the sheet lifting devices are carried, the said columns having short guideways adapted in their upward position to align with the said guideways which extend over the conveyor band.

6. An automatic sheet gathering and collating machine according to claim 2, where- 75 in the sheet lifting device comprises a plurality of suction plates each provided with a suction tube on the under side and a connecting bar upon which said suction plates are adjustably arranged.

7. An automatic sheet gathering and collating machine according to claim 2, where- 80 in the sheet supporting fingers are pivoted to swing in horizontal planes close under the lifted sheet and including air cylinders attached to the sheet lifting means and pistons operated in said cylinders and by which said sheet supporting fingers are actuated.

8. An automatic sheet gathering and collating machine according to claim 2, where- 90 in the sheet supporting fingers are pivoted to swing in horizontal planes close under the lifted sheet and including air cylinders attached to the sheet lifting means and pistons operated in said cylinders and by which said 95 sheet supporting fingers are actuated and also including spring influenced valve and gravity catch devices to control the movements of the sheet supporting fingers.

In testimony whereof he has affixed his 100 signature.

G. W. YOUNG.
